CLAIM

The ornamental design for a casing of a hand held ultrasonic flaw detector instrument, as shown and described.

DESCRIPTION

FIG. 1 is an isometric view of a casing of a hand held ultrasonic flaw detector instrument;
FIG. 2 is front view thereof;
FIG. 3 is back view thereof;
FIG. 4 is left side view thereof;
FIG. 5 is right side view thereof;
FIG. 6 is top view thereof; and,
FIG. 7 is bottom view thereof.

The broken lines illustrate portions of the casing of a hand held ultrasonic flaw detector instrument that form no part of the claimed design.
